By his att'y, J. H. Richard.

UNITED STATES PATENT OFFICE.

JOHN STANLEY HAZELL, OF FOREST GATE, LONDON, ENGLAND, ASSIGNOR TO
UNCHOKEABLE PUMP LIMITED, OF LONDON, ENGLAND.

CENTRIFUGAL PUMP.

Application filed March 12, 1921. Serial No. 451,690.

To all whom it may concern:

Be it known that I, JOHN STANLEY HAZELL, a subject of the King of Great Britain, residing in Forest Gate, London, England, have invented certain new and useful Improvements in and relating to Centrifugal Pumps, of which the following is a specification.

This invention relates to improvements in and relating to centrifugal pumps and it refers particularly to pumps in which the impeller is provided with a single port or opening for the passage of the liquid.

The present invention has for its primary object certain improvements in pumps of this type designed to increase the efficiency thereof by reducing "slip."

The invention further provides improvements enabling the pump to operate effectively when driven in either direction.

According to this invention in order to avoid "slip" the passage in the impeller at the discharge end thereof is provided with one or more radially disposed vanes or projections, or instead of projections the surface of the passage at this point may be corrugated or otherwise shaped or treated to increase the grip upon the liquid.

In order that the invention may be the better understood drawings are appended illustrating the application of the invention to a pump having an impeller of the single passage type.

In the accompanying drawings:—

Fig. 1 is a vertical section taken longitudinally of the shaft of the impeller,

Fig. 2 is a section on line A A Fig. 1.

Referring to the accompanying drawings *a* indicates the shaft of the impeller and *b* the impeller.

Arranged as shown within the port or passage *d* are vanes or projections *e* which are disposed upon opposite sides of the passage and are curved at the ends directed

towards the incoming liquid, as shown, thereby preventing solid or fibrous material from being caught and retained by said vanes. The vanes are of such width as to leave a clear passage or space between them for the ready passage of the material. The vanes or other projections may be radially disposed or they may be radially inclined as shown in Fig. 2. The vanes or the like may be opposite one another as shown or they may be staggered.

Where the pump is to be driven in one direction only the vanes may be curved longitudinally or provided with curved inner surfaces.

Claims:

1. A centrifugal pump comprising an outer case, an inlet to said case, an outlet from said case, an impeller having a single port for the passage of the liquid, projections upon each side of the surface of the passage at the discharge end thereof. 65

2. A centrifugal pump comprising an outer case, an inlet to said case, an outlet from said case, an impeller having a single port for the passage of the liquid and inclined projections upon each side of the passage at the discharge end thereof. 70

3. A centrifugal pump comprising an outer case, an inlet to said case, an outlet from said case, an impeller having a single port for the passage of the liquid, projections upon each side of the surface of the passage at the discharge end thereof, the projections upon one side being arranged in staggered relationship to those upon the other side. 85

In testimony whereof I have hereunto set my hand in the presence of two witnesses.

JOHN STANLEY HAZELL.
